VALVE ORGANIZATION FOR GAS RANGES

Edward E. Hodgkin, William W. Wodell, and
Henry Lange, Quincy, Ill., assignors to Quincy
Stove Manufacturing Co., Quincy, Ill.

Application July 18, 1932, Serial No. 623,162

2 Claims. (Cl. 277—19)

Our invention relates to controls for gas burning equipment and especially to means for controlling the gas supply for the individual burners in a gas range or other gas burning apparatus wherein more than one gas burner may be used.

A purpose of our invention is to provide for gas ranges a gas valve organization which will operate in conjunction with a suitable housing and distributing system in a manner permitting the manipulation of but one handle for the control of any and all burners.

A particular purpose of our invention is to provide a simple, economical, practical and convenient single valve control for the gas supply to the gas burners thus permitting the cook or the operator to control the gas feed to gas burners by manipulating but one dial or handle or other suitable type of single control of the releasing of gases from their source of supply to the respective burners.

We attain the objects of our invention by the apparatus described in the annexed specification, recited in the claims and illustrated in the accompanying drawings in which the same reference numerals indicate like parts in the different figures.

Referring to the figures:

Figure 1 is a perspective showing in cut-a-way of some of the interior details of our invention.

Figure 2 is a front view of the face of the partition wall and control valves of our invention located in their respective positions in the housing.

Figure 3 is a rear view of the housing in our invention and disclosing in a cut-a-way the relative position of the respective gas distributing channels and the orifices through which the gas supply enters the gas chamber from which it is distributed through the channels.

Figure 4 is a perspective of the housing casting of our invention looking into the face of the partition wall.

Figure 5 is a perspective showing the reversed position of the housing casting disclosing from a rear view in a cut-a-way the interior of a rear gas chamber through which the incoming gas enters.

Figure 6 is a view similar to Figure 5 which discloses in cut-a-ways the gas distributing channels in the housing casting.

Figure 7 is a top view of our invention in which there is shown a horizontal cross-section of the cover or hood member which defines the gas chamber housing the control valves of our device.

Figure 8 is a front view of the housing disclosed in part in Figure 2.

Figure 9 is a top view of our invention similar to Figure 7 but showing not only the burner leads connected therewith but also the control handle in cross-section mounted upon a cross-section view of the hood member defining the gas chamber as well as the control shaft and pin for manipulating the gas control valve disc.

Figure 10 is a detailed perspective of one of the gas control valve discs shown in Figure 2.

Figure 11 is a perspective detail of the control shaft supporting the control handle in our device.

Figure 12 is a perspective of the hood member defining the gas chamber in which the control valves operate.

Figure 13 is a perspective of the spring member used for automatically releasing the control shaft and pin from engagement with the gas valves.

Figure 14 is a perspective showing in quarter-section the details of the control dial.

Figure 15 is a perspective of one of the little springs within the gas chamber which are used for holding the valve discs into operative position when assembled.

Referring in detail to the construction of our invention and the preferred manner of manipulating the same we provide in a housing 1 a construction which defines therein a gas chamber 2 and a plurality of gas distributing channels indicated for instance by channels 3, 4, 5, and 6.

This housing has a threaded central connection 7 for the attachment of an incoming gas supply pipe 8. It also is provided with threaded connections 9, 10, 11, and 12 for outlet connections running to the gas burners 13, 14, 15, and 16 respectively. The housing with its assembled connections may be supported on a gas range for instance, by lugs 17, and 18 or other integral lugs if desired, intermediate the ends.

Our purpose being in this case to provide a suitable means of receiving and distributing the gas supply for gas burners by a single valve control, we provide as an integral part of a housing a partition wall 19, over which a hood member 20 may be secured by screws engaging lugs 21, 22, 23, and 24 as they hold hood 20 down through corresponding lugs thereon. This hood 20 when fitted into operative position defines a gas housing chamber into which the gas enters through orifices 25, and 26, from the gas supply pipe 8.

In order to selectively release the gas entering chamber 2 defined by hood 20 out to the respective distributing channels leading to burner connections 13, 14, 15, and 16 we provide gas release

valves, the design and operation of which will now be set forth.

The smooth flat face of partition wall 19 has a flanged perimeter 27 for seating hood member 5 20. Through wall 19 gas release holes 28, 29, 30, and 31 are drilled so as to provide a passage for the escape of gases leading to the gas outlets 9, 10, 11, and 12. It is for the selective control of the release of gases from chamber 2 therefore 10 that our device is designed.

It will be observed that we have provided as a means of optionally releasing gases from chamber 2 a gas control valve organization including a group of pivoted valve discs 32, 33, 34, and 35 15 resting against the smooth face of wall 19 and supported on pivot pins 36, 37, 38, and 39 each of which are provided with a spring 40 held down by hood 20 so as to resiliently hold down the valve discs supported by the pivot pins.

20 Each of these valve discs is provided with a hole 41 off center adapted to be moved pivotally over into co-registry with the approximate one of holes 28, 29, 30, and 31 in wall 19 in order to permit the gases to pass from chamber 2 through wall 19 out into one of the gas distributing channels 3, 4, 5, and 6.

25 It will be noted that holes 28, 29, 30, and 31 are normally covered by valve discs 32, 33, 34, and 35 respectively; thus to prevent the gas in chamber 2 from escaping unless released at will.

30 In Figure 9 it will be noted that a control shaft 42 is normally held resiliently out as far as it can go along with dial 43 by a compression spring 44 mounted between hood 20 and dial 43. This 35 action is for the purpose of holding pin 45 away from engagement with the valve discs 32, 33, 34, and 35.

35 However when it is desired to light a burner with which our device is operatively connected 40 requiring the releasing of gas to the burner the one lighting the burner (a pilot light is usually provided for igniting the gas) will press in on dial 43 moving pin 45 into engagement with the inner peripheral recess 46 of one of the valve discs; the disc controlling the gas outlet that 45 leads to the burner that it is desired to light.

50 When pin 45 is thus placed in to recess 46 of the valve disc to be controlled; then by turning the dial 43 this valve disc will be movable pivotally to the right or left. In this manner then, 55 for instance, disc 34 (see Figure 2) may be pivotally moved until the gas releasing aperture therein is moved over into co-registry with hole 30 in partition wall 19; thus permitting the gas to escape out through channel 4 connected with burner 13.

55 It will be observed that the volume of burner blaze may be varied by placing the hole in the valve discs in any desired position of partial or 60 complete registry with the gas releasing holes in wall 19 under the valve discs.

65 It will be noted that an integral bearing 47 is provided in the housing for the slidable support of shaft 42.

65 It will be further observed that it is possible to move the valve discs pivotally by slidably moving pin 45 into the space between adjacent disc

members and then rotating the dial so as to move the pin over against the curved edge of the disc. Thus by exerting a rotating pressure against the disc the pin may move the disc in the desired direction depending on which side of the axis 5 of the disc the pressure is made on.

It is conceivable that within the scope of our invention the form of the housing could be varied as well as the type of channel members leading to the gas burners; while a careful study 10 of the features illustrated will disclose other details of our invention which may be changed without departing from the spirit of our invention.

Having thus described the nature of our invention what we claim is:

1. In a gas range having a control valve housing defining a gas receiving chamber, a partition wall, and a plurality of integral gas distributing channels, and the partition wall provided with 20 a plurality of concentrically disposed gas releasing holes arranged in predetermined spaced relation; a gas control valve organization comprising a plurality of pivoted valve disks pivotally secured to said partition wall adjacent 25 corresponding holes therein and each of said disks provided with a gas releasing aperture pivotally movable selectively into coregistry with said adjacent corresponding gas releasing hole respectively in the partition wall of said housing, 30 a peripheral recess in each of said disks for rotatably receiving the end of a control pin adapted to actuate the disks, respectively, a control shaft for the support of the pin and a hand dial supported thereby, a disengaging spring for automatically releasing said control shaft when pressure is released therefrom and an individual spring for each of said valve disk members holding 35 said members flatly against the adjacent surface of said partition wall.

2. In a gas range a housing for a gas control valve mechanism and provided with a partition wall having a plurality of gas releasing apertures and a faced surface, a gas control valve organization comprising a plurality of pivoted valve disks pivotally secured to said faced partition wall respectively adjacent corresponding gas releasing apertures therein, each of said valve disks provided with an aperture adapted to be selectively moved into co-registry with said corresponding gas releasing aperture in said partition wall for releasing gases from said gas chamber, a control shaft and a control pin for actuating said disks by a slidable adjustment of the shaft and a rotatable movement of the pin against a peripheral recess provided in each of said disks, a spring for automatically removing said control pin from contact with said disks respectively when not under manual control, a single dial on said shaft for the selective adjustment of any 60 and all of said disks respectively and a spring on each disk for holding the same snugly against said faced surface of said partition wall.
